CLAIM

The ornamental design for a straw lid, as shown and described.

DESCRIPTION

FIG. 1 is a perspective view of a straw lid showing our new design, with a straw member in an extended position.

FIG. 2 is a front view of the straw lid of FIG. 1.

FIG. 3 is a rear view of the straw lid of FIG. 1.

FIG. 4 is a left side view of the straw lid of FIG. 1.

FIG. 5 is a right side view of the straw lid of FIG. 1.

FIG. 6 is a top plan view of the straw lid of FIG. 1.

FIG. 7 is a bottom plan view of the straw lid of FIG. 1.

FIG. 8 is a perspective view of the straw lid with the straw member in a flat position.

FIG. 9 is a front view of the straw lid of FIG. 8.

FIG. 10 is a rear view of the straw lid of FIG. 8.

FIG. 11 is a left side view of the straw lid of FIG. 8.

FIG. 12 is a right side view of the straw lid of FIG. 8.

FIG. 13 is a top plan view of the straw lid of FIG. 8; and,

FIG. 14 is a bottom plan view of the straw lid of FIG. 8.

The broken lines in the drawings depict portions of the straw lid that form no part of the claimed design.

1 Claim, 14 Drawing Sheets
